Primary Examiner — Melanie Pellegrini

(74) *Attorney, Agent, or Firm* — Fredrikson & Byron, P.A.

(57) **CLAIM**

I claim the ornamental design for a pendant, as shown and described.

DESCRIPTION

FIG. 1 is a front view of my new design for a pendant;
FIG. 2 is a rear view thereof;
FIG. 3 is a top view thereof;
FIG. 4 is a bottom view thereof;
FIG. 5 is a first side view thereof;
FIG. 6 is an opposite side view thereof;
FIG. 7 is a front view of my new design for a pendant according to another embodiment;
FIG. 8 is a rear view thereof;
FIG. 9 is a top view thereof;
FIG. 10 is a bottom view thereof;
FIG. 11 is a first side view thereof;
FIG. 12 is an opposite side view thereof;
FIG. 13 is a front view of my new design for a pendant according to another embodiment;
FIG. 14 is a rear view thereof;
FIG. 15 is a top view thereof;
FIG. 16 is a bottom view thereof;
FIG. 17 is a first side view thereof; and,
FIG. 18 is an opposite side view thereof.

The broken lines shown in the drawings represent unclaimed portions of the pendant and form no part of the claimed design.
